Inventor:

Jacob H. Schuster Inventor.

UNITED STATES PATENT OFFICE

JACOB H. SCHUSTER, OF ST. LOUIS, MISSOURI

RECIPROCATING-ACTION SAFETY RAZOR

Application filed October 28, 1929. Serial No. 402,840.

This invention relates to improvements in a reciprocating action safety razor, and consists in the novel arrangement, construction and combination of parts as will be more fully hereinafter described and set forth in the claims.

The object of my improved razor is to provide an equipment whereby a reciprocating action is imparted during the act of shaving, thus creating a cutting action instead of that of scraping as its the case where the ordinary safety razors are used.

By my invention, the hair on the face is cut close to the skin by a reciprocating or cutting action instead of the usual scraping or pulling method, thus it will not pull the hair nor smart the skin, but on the contrary, produces a smooth non-irritating shave.

The razor is held by the thumb and forefinger, and by means of another finger of the same hand, positioned in the loop member the blade supporting member is reciprocated or in other words is placed in a sliding action against the face, thus producing a cutting effect the same as if an ordinary old fashioned razor was being used.

The razor is equipped so that it will accommodate the insertion of any thickness of finger, and can be adjusted so that it may be used by the right or left hand.

The essential feature of my invention is to provide a safety razor with a blade supporting member and a sliding frame the same to be held by three fingers and manipulated so that it creates a cutting effect instead of scraping.

Figure 1, is a perspective view of my complete invention.

Figure 2, is a top plan view of the same.

Figure 3, is a side view.

Figure 4, is a central sectional view.

Figure 5, is an end view.

Figure 6, is a central cross sectional view on a somewhat larger scale.

Figure 7, is a perspective view of the locking nut made use of.

Figure 8, is a perspective view of the top member with the handle or loop section cut away.

Figure 9, is a perspective view of the slid-

ing frame made use of to create the reciprocating effect.

Figure 10, is perspective view of the razor blade.

Figure 11, is a perspective view of the blade supporting member.

Figure 12, is an end view showing the manner in which the finger support may be adjusted.

In the general construction of my invention I provide a reciprocating action safety razor consisting of a base or blade supporting member 13; it is provided with a screw threaded post 14, and a stud 15; the under or contacting surface of the member is provided with elongated grooves 16 extending the full length of the member and is for the purpose of preventing the member from sticking to the face when brought in contact therewith as the said grooves admit air to pass therein and avoiding suction. The corners are sufficiently rounded as indicated by the numeral 17 so as not to scratch the skin.

On this member is placed the razor blade 18 which is equipped with perforations to correspond with the post and stud of the base member.

On top of the blade and over the post is placed a sliding member 19 having an elongated slot 20 for free movement around the post 14. The edges of the member are turned under forming slides 21 which contact immediately on the top of the blade, thus relieving much friction during the operation.

The end of the member is provided with a finger grip 22 which is gripped by the thumb and forefinger.

When this member has been placed in position, the top member 23 is added; this member is suitably bent to fit over the sliding member and its edges are provided with teeth 24 which project beyond the cutting edge of the blade acting as a safety means; at the ends of the rows of teeth, a prong 25 is formed, the prongs are arranged horizontally and so shaped to protect the extreme corners of the blade so as to avoid cutting the skin.

This member is also provided with perforations to permit the member to be placed

over the post and stud formed on the base member.

When the several members have been placed together, they are held in assembled position by the locking nut 26, and the curvature of the blade is adjusted by the application and adjustability of said locking nut 26 placed on the post 14.

The top member is equipped with an upturned end 27, to which is pivotally connected an adjustable loop construction 28 consisting of two members 29 and 30, the free end of the member 29 carrying a loop 31 and through it is passed the free end of the member 30. By this arrangement the arms comprising the loop 28 can be spread or closed to accommodate the thickness of the finger to be inserted therein, and by means of the pivotal arrangement, the proper angle may be attained to suit the shaving position desired by the user.

In operating the razor, the user grips the finger grip 22 between the thumb and forefinger, and then inserts one of the other fingers into the loop 28, then by parting and closing the fingers, a reciprocating action is imparted, and when the razor is applied to the face, it creates a cutting effect by means of this reciprocating movement which is now void in all present standard safety razors, as their method is of the hoeing or scraping effect.

This razor has a unique principle, it is compact and easy to manipulate, and has a smooth cutting action.

Having fully described my invention what I claim, is:

1. A reciprocating razor comprising a base member, a center post and a lug formed thereon, the under surface of said base member provided with parallel curvilinear grooves, a razor blade positioned on the base member and supported by the post and stud, a slotted sliding member positioned on the razor blade and guided by the post and stud, an upturned finger grip formed on the end of said sliding member, a top member positioned over the sliding member, its side edges bent downwardly and formed into teeth, an adjustable loop member formed on the top member, and a lock nut positioned on the post for holding the parts in assembled position, substantially as specified.

2. A razor of the character described comprising a slightly concavo-convex base member, a razor blade seated on the concave surface of said base member, an elongated centrally slotted sliding member positioned on the razor blade, a pair of slides formed on the under surface of the sliding member and designed to rest on the blade, an upturned finger grip formed on one end of the sliding member and to be gripped between the thumb and forefinger, a top member positioned over the sliding member, an adjustable loop mem-

ber connected to one end of the top member, said loop arranged to accommodate the insertion of either the third, fourth or little finger of the same hand, and a lock nut positioned on a post formed on the base member for holding the several parts in assembled position, substantially as specified.

3. A razor of the reciprocating type comprising a base member, a sliding member, and a top member, a razor blade firmly positioned on the base member, a post and stud formed on the base member and by which the blade is held rigid, the sliding member arranged to slide between the blade and top member its movement limited by an elongated slot formed in said sliding member, a finger grip formed on one end of the sliding member and to be held between the thumb and fore-finger, an adjustable loop attached to one end of the top member and in which may be inserted either one of the third, fourth or little finger of the same hand, the reciprocatory movement being accomplished by the closing and spreading of the fingers, and a lock nut for holding the assembled members in position, substantially as specified.

4. A reciprocating action safety razor comprising an upper member its sides provided with teeth, an adjustable loop formed on one end thereof, a reciprocating member, a finger grip formed on one end thereof, a base member, a double edge razor blade positioned between the reciprocating and base members, action imparted to the razor by spreading and closing the fingers at the same time gripping the finger grip and loop, and a lock nut for holding the members in assembled position, substantially as specified.

In witness whereof I have hereunto set my hand this 9th day of Oct., 1929.

JACOB H. SCHUSTER.
